Primary Examiner—Stella M Reid*Assistant Examiner*—Shanda C Hill(74) *Attorney, Agent, or Firm*—McDonnell Boehnen Hulbert & Berghoff LLP**CLAIM**

The ornamental design for a beverage can, as shown and described.

DESCRIPTION

FIG. 1 is a side elevation of a beverage can showing my new design;

FIG. 2 is a perspective view thereof; and,

FIG. 3 is a top plan view thereof.

The bottom of the can forms no part of the design.
